US00D910938S

(12) **United States Design Patent** (10) **Patent No.:** **US D910,938 S**
Jakubowski et al. (45) **Date of Patent:** **** Feb. 16, 2021**

(54) **PET RAMP**

(71) Applicant: **Vermont Juvenile Furniture Mfg., Inc.**, West Rutland, VT (US)
(72) Inventors: **Chris Jakubowski**, Rutland, VT (US); **Todd Jakubowski**, Rutland, VT (US); **Kristen Jakubowski**, Rutland, VT (US)

(73) Assignee: **Vermont Juvenile Furniture Mfg., Inc.**, West Rutland, VT (US)

(**) Term: **15 Years**

(21) Appl. No.: **29/685,120**

(22) Filed: **Mar. 26, 2019**

(51) LOC (13) Cl. **30-99**

(52) U.S. Cl.

USPC **D30/199**

(58) **Field of Classification Search**

(57) **CLAIM**

The ornamental design for a pet ramp, as shown and described.

DESCRIPTION

FIG. 1 is a side perspective view of a pet ramp in accordance with our new design;

FIG. 2 is a front view of the pet ramp shown in FIG. 1; FIG. 3 is a rear view of the pet ramp shown in FIG. 1; FIG. 4 is a first side view of the pet ramp shown in FIG. 1; FIG. 5 is a second side view of the pet ramp shown in FIG. 1;

FIG. 6 is a top view of the pet ramp shown in FIG. 1; FIG. 7 is a bottom view of the pet ramp shown in FIG. 1; FIG. 8 is a bottom perspective view of the pet ramp shown in FIG. 1 in a collapsed position; and, FIG. 9 is a top perspective view of the pet ramp shown in FIG. 1 in the collapsed position.

All broken lines appearing in the drawings are for illustrative purposes and/or represent unclaimed subject matter and form no part of the claimed design.
